UNITED STATES PATENT OFFICE.

ROSE KOSLOFF, OF JAMAICA, NEW YORK.

WATERPROOF BABY PANTS.

Application filed July 22, 1927. Serial No. 207,588.

My present invention relates generally to infants' clothing, and has particular reference to waterproof baby pants.

The ordinary employment of diapers of absorbent material is frequently accompanied by the added employment of rubber or waterproof devices, such as pants, particularly where the infant is being transported from place to place, and in general, whenever it is inexpedient promptly to attend to a change of diapers. The waterproof device is of course a protection for the body and clothing outside of the device, but although the outside area is thus protected, the infant's body, through constant contact with the absorbent—particularly after the latter is wet—is subjected to chafing and general discomfiture which is not only unpleasant but decidedly un-
sanitary.

One object of the present invention is to provide a device having all the desirable characteristics of ordinary waterproof pants or similar protections, and having structural features which tend to relieve the disadvantages illustratively mentioned above.

Briefly, my invention contemplates the provision of a waterproof device having a double bottom, the outer bottom serving in one sense as the equivalent of the ordinary bottom of plain pants, and the inner bottom serving as a protective layer for the infant's body itself; the absorbent being accommodated between the bottoms. To render the absorbent useful and effective, I provide a series of relatively small perforations in the inner bottom, whereby the absorbent itself will be constantly separated from contact with the baby's body.

One feature of my invention resides in providing a structure wherein a body portion including the usual leg openings and including the inner bottom referred to, is composed of an integral layer of material.

Another feature of my invention resides in providing the outer bottom as a separate layer of similar material, this underlay being marginally attached to the body portion in such a manner that the absorbent element or pad between the bottoms will be securely retained against all of the perforations.

Other features of my invention reside in the structural nature which renders the complete device inexpensive and simple of construction, yet highly efficient in use.

For the attainment of the foregoing ob-

jects and such other objects as may herein-after appear or be pointed out, I have illustrated one form of my invention in the accompanying drawings in which—
60

Fig. 1 is a perspective view of a device embodying the features of my invention;

Fig. 2 is a rear elevational view thereof with a portion broken away; and

Fig. 3 is a vertical cross-section taken substantially along the line 3—3 of Figure 2.
65

An integral sheet 10 of suitable waterproof material such as rubberized fabric or the like is cut and shaped into pants form including usual leg openings 11 and a waist 70 opening 12. The bottom of this body portion, and more particularly, the bottom which lies between the leg openings 11 is provided with a series of relatively small perforations 13.
75

A layer of similar material 14, shaped and constructed to constitute a second or outer bottom, is suitably attached in an underlying manner to the body portion 10 to provide a pocket between the first-named or 80 inner bottom and the outer bottom provided by the layer 14. The element 14 is substantially rectangular, having a rear edge 14', side edges 15, and a forward edge 16. It is marginally attached to the body portion 85 10 along the rear edge 14' and along substantially the entire extent of the side edges 15. This attachment may be effected by a line of stitching 17, and it will be noted that this stitching does not extend for the complete length of the longitudinal edges 15, but terminates at points 18 which leave forward portions 19 of the side edges 15 unattached to the body portion.
90

The portions 19, together with the front 95 edge 16, define a manipulable flap 20, and this flap is provided with means, such as the snap fasteners 21, for detachably securing it to the body portion.

The pocket between the inner and outer 100 bottoms is designed to receive an element of absorbent material 22, and the insertion and removal of this element or pad is designed to be effected through the opening provided by the turn-down flap 20 (see 105 Figure 3). It will be noted that the points 18, at which the stitching 17 ends, are so positioned that the major portion of the layer 14 is firmly secured in an underlying manner to the inner bottom. In this way, the absorbent element 22 is firmly retained 110 against all of the perforations 13.

The advantages of the device will be apparent from the description given. It is to be noted that the element 22 is protected from contact with the body of the infant, 5 and accordingly undesirable chafing which might be caused by such contact is totally avoided. At the same time, the element 22 is securely retained within the pocket when the device is in use, and in this way, the device 10 fulfills the desirable functions of an ordinary pair of rubberized or waterproof pants.

It will be obvious that many changes in the details herein described and illustrated 15 for the purpose of explaining the nature of my invention may be made by those skilled in the art without departing from the spirit and scope of the invention as expressed in the appended claims. It is theretofore intended that these details be interpreted as 20 illustrative and not in a limiting sense.

Having thus described my invention and illustrated its use, what I claim as new and desire to secure by Letters Patent is—

25 1. A pair of waterproof baby pants comprising a body portion of non-absorbent waterproof material which includes spaced leg openings, the bottom between said openings being perforated; and an additional 30 and unperforated bottom portion, also of nonabsorbent waterproof material, underlying said first-mentioned bottom at only approximately the crotch portion of said pants to provide a pocket between said bottoms for 35 the reception of absorbent material; said underlay having its opposite side edges securely attached to the body portion throughout an extent which retains said absorbent

material firmly against all the perforations, and the end portion of said underlay being 40 provided with means for detachably securing it to the body portion.

2. A pair of waterproof baby pants comprising a body portion of non-absorbent waterproof material which includes spaced 45 leg openings, the bottom between said openings being perforated; and an additional and unperforated bottom portion, also of non-absorbent waterproof material, underlying said first-mentioned bottom at only 50 approximately the crotch portion of said pants to provide a pocket between said bottoms for the reception of absorbent material; said underlay having its medial portion securely attached at its edges to the 55 body portion, and having an end portion provided with means for detachably securing it to the body portion.

3. A pair of waterproof baby pants having the usual leg openings and provided 60 with a double bottom therebetween for the reception of an absorbent pad; the inner bottom having a series of relatively small perforations therein and the outer bottom being unperforated; whereby the baby's body, and also the area outside of the pants, is protected from contact with the absorbent material; said outer bottom being detachable at least in part from said inner bottom to provide ready access to the space between said bottoms while said pants are 65 in position on the body of the baby.

In witness whereof I have signed this specification this 20 day of July, 1927.

ROSE KOSLOFF.
